UNITED STATES PATENT OFFICE

166,941

TEXTILE FABRIC OR SIMILAR ARTICLE OF MANUFACTURE

Lou Appleton, New York, N. Y.

Application November 19, 1949, Serial No. 6,145

Term of patent 14 years

(Cl. D92—1)

To all whom it may concern:

Be it known that I, Lou Appleton, a citizen of the United States of America and resident of the city, county, and State of New York, have invented a new, original, and ornamental Design for a Textile Fabric or Similar Article of Manufacture, of which the following is a specification, reference being had to the accompanying drawing, forming a part thereof.

Figures 1 and 1A, taken together and joined at lines A—A, is a plan view of a textile fabric or similar article of manufacture, showing my new design. A complete design unit is contained between the broken lines and is repeated as indicated.

I claim:

The ornamental design for a textile fabric or similar article of manufacture, as shown and described.

LOU APPLETON.
